UNITED STATES PATENT OFFICE.

OTTO F. STONEBURNER, OF ZANESVILLE, OHIO.

DOOR-HANGER AND TRACK THEREFOR.

No. 845,206.

Specification of Letters Patent.

Patented Feb. 26, 1907.

Application filed February 1, 1906. Serial No. 298,902.

To all whom it may concern:

Be it known that I, OTTO F. STONEBURNER, a citizen of the United States, residing at Zanesville, in the county of Muskingum and State of Ohio, have invented a new and useful Improvement in Door-Hangers and Tracks Therefor, of which the following is a specification.

My invention relates to improvements in door-hangers and in tracks for said hangers to run on; and the objects of my invention are, first, to prevent the hanger-wheel from jumping from its said track; second, to prevent the door from swinging outward at either the bottom or the top when all other stays fail, and third, to prevent the door from dropping at either, or both, sides if other supports fail.

I obtain these objects by the mechanism illustrated in the accompanying drawings, in which—

Figure 1 is a perspective view of my improved door-hanger and track therefor from the inside with parts broken away. Fig. 2 is a vertical sectional view through the axle of hanger-wheel 3.

Similar numerals refer to similar parts throughout the several views.

Door 1 is fixed to hanger-arm 2, which is provided with wheel 3 and guides or arms 4, having acute-angled or beveled lugs 5, adapted to receive into their said acute angles the corresponding y-beveled side or portion 9 of longitudinal shoulder or abutment 8, abruptly projecting downward from the under face of the horizontal portion of track-bracket 6 and forming or leaving a space between its said beveled side and the said horizontal portion of track-bracket 6 of a size and form sufficient to receive said beveled lugs 5 and to allow them to move therein, clear of all adjacent parts, back and forth as the door is normally opened and closed by rolling said wheel 3 on track-rail 7, formed on the upper face of the horizontal portion of track-bracket 6. Said horizontal portion of track-bracket 6, its longitudinal shoulder or abutment 8, with beveled side 9, and arms 4 and vertical portion or body of hanger-arm 2 are of such formations and dimensions that beveled side 9 is adapted to form a locking-seat

for correspondingly-beveled lugs 5 if wheel 3 or the parts sustaining it should break, thereby retaining hanger-arm 2 and its door in an operative position on track-bracket 6 until said wheel, &c., can be economically repaired. Said longitudinal shoulder or abutment 8, with its beveled side 9, is further adapted to resist and stay the outward swing of beveled lugs 5, and thereby of hanger-arm 2 and the door, and also to resist and stay the upward jump of arm 4, and thereby of hanger-arm 2 and its said wheel. Track-rail 7 prevents wheel 3 from running so near the edge of the horizontal portion of track-bracket 6 as to cause beveled lugs 5 frictionally to engage and bind on beveled side 9.

What I claim as my invention, and desire to secure by Letters Patent, is—

The combination with a track-bracket 70 having a horizontal portion with a track-rail on its upper face and with, on its under face, a longitudinal shoulder or abutment having a beveled side, and with a space or way between said beveled side and horizontal portion, of a hanger-arm provided with arms having lugs beveled correspondingly to the beveled side of the longitudinal shoulder or abutment, said hanger-arm also having a wheel with a groove to correspond to said 80 track-rail, and the formations and dimensions of said engaging parts being such as to adapt the hanger-arm to be hung on the track-bracket, the wheel to engage the track-rail, the beveled lugs to move, normally, in 85 said space or way, the longitudinal shoulder or abutment with its beveled side, normally, to stay the outward swing of the beveled lugs and the door, and the upward jump of lug-bearing arms and the hanger-arm and its 90 wheel; and the beveled side of the longitudinal shoulder or abutment to become a locking-seat for the beveled lugs, all substantially as described.

In testimony whereof I have signed my 95 name to this specification in the presence of two subscribing witnesses.

OTTO F. STONEBURNER.
